United States Patent Office

Des. 197,887
Patented Apr. 7, 1964

197,887

REAR VIEW MIRROR

Wallace W. Ward, Chatham Township, Morris County, N.J., assignor to Diecasters, Inc., Closter, N.J., a corporation of New Jersey

Filed Aug. 29, 1961, Ser. No. 66,532

Term of patent 14 years

(Cl. D14—6)

FIG. 1

FIG. 2

FIG. 1 is a front perspective view of a rear view mirror shown in my new design.

FIG. 2 is a bottom perspective view of the same mirror.

The upper mirror is flat and vertically positioned while the lower mirror is both transversely and longitudinally convex.

I claim:

The ornamental design for a rear view mirror, as shown and described.
